CUSHIONED ESCAPEMENT SUPPORT

Frederick W. Schremp, Elmira, N. Y., assignor to
Remington Rand Inc., New York, N. Y., a corporation of Delaware

Application December 22, 1948, Serial No. 66,672

4 Claims. (Cl. 197—82)

1

This invention relates to a construction for mounting a typewriter carriage escapement on the typewriter frame.

The invention provides a mounting for a typewriter escapement on the typewriter frame and includes means for absorbing the shock and materially reducing the noise produced in the operation of the escapement. The escapement mounting provides means for attaching the escapement bracket to the frame of the typewriter by resilient means and provides for limited movement of the supporting plate for the escapement relative to the typewriter frame and at the same time absorbs the shock producing this limited movement and normally maintains the supporting plate for the escapement in a fixed position with relation to the typewriter frame.

In carrying out this shock absorption and noise elimination in the mounting of the typewriter escapement, the supporting plate for the typewriter escapement may be mounted in surface contact with a plate portion or back portion of the typewriter frame and resiliently retained in frictional engagement against the back portion of the typewriter frame by any suitable means that will permit limited movement with the frictional engagement between the supporting plate and frame. Resilient members such as rubber plugs may be inserted in registering openings in both the escapement supporting plate and the plate portion on the typewriter frame in transversely extending relation so that these parts may be compressed into registering openings to have firm engagement with both plates about the portions defining the openings for absorbing shocks and relative movement of the supporting plate and normally maintaining the supporting plate in a fixed relation with respect to the plate portion of the typewriter frame.

In the drawings:

Fig. 1 shows a rear elevation of the frame of a typewriting machine with the invention applied thereto, illustrating how the escapement assembly is supported on the back plate of the machine by the means provided by the invention, other portions of the typewriter being omitted.

Fig. 2 is an enlarged rear view of the escapement mechanism with the rocker bracket on which the mechanism is assembled shown in dot and dash lines for clearly illustrating the escapement assembly and the manner in which it is mounted on the rocker bracket and supporting plate according to the invention.

Fig. 3 is a side elevation of the structure shown in Fig. 1, taken substantially on line 3—3 of Fig. 1.

2

Fig. 4 is an enlarged vertical cross-section through one of the cushion supports and supporting plate retaining members, taken substantially on line 4—4 of Fig. 1 and illustrating the method of resiliently mounting the escapement mechanism on the back plate of the typewriter.

Fig. 5 is a horizontal cross-section through the pivotal mounting of the escapement rocker taken substantially on line 5—5 of Fig. 2.

Fig. 6 is a vertical cross-section taken substantially on line 6—6 of Fig. 2.

The typewriter frame construction and escapement mechanism illustrated in the drawings shows the construction in current commercial use on the Remington standard typewriter, model number 17, and illustrates the application of one form of the invention to this standard typewriter, although it is to be understood that it may be readily adapted to other makes of typewriters.

20 The escapement mechanism shown in the drawings has an escapement rocker bracket 1 mounting the escapement wheel bearing shaft 2 for rotatably supporting the escapement wheel assembly 3. The escapement wheel assembly includes escapement wheel 4, and gear 5 assembled in rigid relation. The teeth of gear 5 intermesh with the teeth of carriage supported rack bar 6. Rack bar 6 forms part of the carriage structure and in cooperation with the escapement mechanism controls the letter spacing movement of the carriage in a manner well-known in the art. The escapement wheel assembly also includes a silencer mechanism, indicated generally at 7 in Fig. 3, for cooperation in controlling the operation of loose dog 8.

A rocker 9 is formed with bearing projections 10 for receiving pivot screws 11 carried by rocker bracket 1 for pivotally mounting rocker 9 on rocker bracket 1. An arm 12 is pivotally mounted on rocker 9 and secured thereto by screw 13 threaded in rocker 9. The free end of arm 12 pivotally supports loose dog 8 at the upper end thereof as shown in Fig. 2 on pivot pin 14.

40 Loose dog 8 has an arm 15 formed with a tooth 16 on the free end for engagement with the radial teeth of escapement wheel 4 for controlling rotation of the escapement wheel. Loose dog 8 has a depending arm 17 connected by tension spring 18 to bracket 19 formed with projections 50 for limiting movement of loose dog 8 by engagement with arm 15 so as to accurately guide arm 15 in its movement on pivot pin 14 in controlling operation of the escapement wheel.

A toggle 20 has one end pivotally connected to 55 arm 12 supporting loose dog 8, about midway be-

tween pivot screw 13 and pin 14, while the opposite end is pivotally connected to rocker 9 by pivot screw 21. A spring 22 has one end secured to the joint for toggle 20 and the opposite end secured to rocker 9 for normally breaking the joint in toggle 20 and moving loose dog 8 with arm 12 to the right as shown in Fig. 2. When toggle 20 is moved into its straightened position it limits movement of loose dog 8 and arm 12 to the left as shown in Fig. 2, through carriage operation of the escapement wheel when one of the escapement teeth is engaged with projection 16 of dog 8.

A cushion plate 23 is mounted on the face of rocker 9 in opposed relation to the adjacent face of rocker bracket 1 by pivot screw 21 at one end and by another screw at another portion thereof in spaced relation to screw 21. Suitable rocker limiting screws are mounted in bracket 1 for engagement with cushion plate 23 in a manner well-known in the art for limiting the rocking movement of rocker 9 on pivot pins 11 in operation of the escapement mechanism.

Compression spring 24, Fig. 2, is engaged between the upper portion of rocker 9 and rocker bracket 1 for normally actuating rocker 9 in one direction on pivot screws 11. Rocker 9 has a projection 25 extending laterally therefrom for engagement by lever mechanism operated by the space bar of the typewriter for moving the rocker on pivot screws 11 in letter spacing operation of the carriage in a manner well-known in the art and as employed in the aforementioned Remington typewriter. Rocker 9 is formed with a recess 26, Fig. 2, for receiving a link operated by the universal bar of the typewriter retained in the recess by arm 27 which may have its free end moved upwardly, from the position shown in Fig. 2, to close the opening of the recess and retain the link operably engaged with rocker 9. The universal bar is operated in a well-known manner by the operation of a type bar of the typewriter and produces a letter spacing movement of the carriage for each type bar operation in printing a letter on a sheet carried by the platen mounted in the carriage. This structure is not shown because it is well known in the art and forms no part of the present invention.

Rocker 9 is formed with fixed dog 28 for cooperation with loose dog 8 in the oscillating movement of rocker 9 for cooperation in a well-known manner with the teeth on escapement wheel 4 in controlling letter spacing movement of the carriage through rack bar 6. The spring drum for producing movement of the typewriter carriage in one direction in the usual manner is shown diagrammatically at 29 in Fig. 1, and has the usual connection with the carriage.

In the operation of the typewriter the oscillating movement of rocker 9 will alternately disengage loose dog 8 from a tooth on escapement wheel 4 and move the rocker into position for engagement of fixed dog 28 with the released tooth on the escapement wheel. Then upon further operation the rocker will move in the opposite direction to release the loose dog 28 from the tooth engaged therewith and move projection 16 into engagement with the next tooth on escapement wheel 4 in completing one cycle of escapement operation and producing one letter space movement of the carriage under operation of the spring in spring drum 29. This movement of the carriage by spring drum 29 in cooperation with the movement of the parts of the escapement mechanism produces the letter

spacing operation in such a way that loose dog 8 with toggle 20 and arm 12 acts to arrest the movement of the carriage with the parts positioned, as shown in Fig. 2, at the end of each letter space movement. This operation of the escapement mechanism is well-known in the art. With rocker bracket 1 mounted on the frame of the typewriter in the usual manner well-known in the art, the escapement operation produces a substantial amount of noise. It is the purpose of the present invention to provide a mounting for this escapement mechanism that will substantially eliminate the noise and absorb vibration and shocks from the operation of the escapement mechanism and thereby produce a carriage and escapement operation of a substantially quiet character.

One embodiment of the invention is illustrated in the drawings and provides a rocker bracket supporting plate 30 of substantially U-shaped construction. Supporting plate 30 has a pair of upwardly extending arms 31 with connecting portion 32 securing the lower ends together. Rocker bracket 1 is secured to the upper ends of arms 31, as shown in Fig. 1, by means of suitable bolts and nuts indicated at 33. The escapement mechanism is supported by supporting plate 30 in the space between arms 31 above connecting portion 32, as clearly illustrated in Figs. 1 and 2, so that the parts associated with the escapement mechanism can be readily connected thereto with portions extending through the space between arms 31 to provide for the convenient mounting and operation of the typewriter parts associated with the escapement mechanism.

Rocker bracket supporting plate 30 is mounted with the inner face of the plate engaged with the rear face of back plate 34 of the typewriter frame. Plate portion 34 of the typewriter frame is constructed to provide face to face contact with supporting plate 30 in order to fix the position of supporting plate 30 with respect to the typewriter frame and to fix the position of the escapement mechanism with respect to the other operating parts of the typewriter. Supporting plate 30 is secured to back plate 34 by a plurality of shouldered screws 35. Screws 35 have an enlarged head extending substantially beyond the shank portion and the shank portion is formed with a reduced threaded end providing a shoulder, see Fig. 4. The reduced threaded end of each screw 35 is threaded into an opening in back wall 34 so that washer 36 engages between the outer rear face of back plate portion 34 and the shoulder on screw 35. Each screw 35 extends through an opening in supporting plate 30, indicated at 37, Fig. 4.

Each of the openings 37 is larger than the shank of screw 35 extending therethrough in order to provide for limited edgewise movement of plate 30 relative to back plate 34 in frictional contact with back plate 34. Each screw 35 has a compression spring 38 engaged between the head thereon and a washer 39 engaged with the periphery of supporting plate 30 about aperture 37. Compression spring 38 and washers 36 and 39 cooperate with each screw 35 to retain supporting plate 30 in firm frictional engagement with the rear face of back plate 34, at the same time providing for limited movement of plate 30 relative to back plate 34 with frictional engagement of the plates tending to prevent the relative movement. As illustrated in the drawings three screws 35 with assembled springs 38 and

washers 36 and 39 are used in securing rocker bracket supporting plate 30 to back plate 34.

Plates 30 and 34 are formed with registering apertures 40 in each arm 31 adjacent the lower end thereof immediately below a pair of the screws 35 securing the upper ends of the arms to back plate 34. Resilient rubber plugs 41, Fig. 4, are inserted in registering apertures 40 and have compression washers 42 engaged with opposite ends thereof on opposite sides of assembled supporting plate 30 and back plate 34, as shown in Fig. 4. A compression bolt 43 threadedly receiving a pair of nuts 44 is arranged in axially extending relation through each rubber plug 41 and the associated compression washers 42 for tightening of the nuts 44 on each bolt 43 to compress resilient plugs 41 to firmly engage the peripheries or edges of supporting plate 30 and back wall 34 in registering apertures 40. This engagement of the rubber plugs with the edges of plates 30 and 34 in the apertures 40 serves to firmly retain supporting plate 30 in a substantially fixed relation on the rear face of back plate 34 against relative movement, but permits of a slight edgewise movement of supporting plate 30 relative to plate 34 in frictional engagement therewith for absorbing shocks applied to plate 34 in the operation of the escapement mechanism and the carriage of the typewriter. Rubber plugs 41 serve to return plate 30 to its original position after each vibratory movement thereof in absorbing shock. It has been found that this mounting of plate 30 on plate portion 34 of the typewriter frame through the medium of screws 35 with compression springs 38 and compressed resilient plugs 41 not only absorbs the shock from the operation of the carriage and escapement mechanism but also absorbs noise vibrations transmitted through rocker bracket 1 to supporting plate 30 and prevents transmission thereof to plate portion 34 and the frame of the machine for amplification of the sound. As a result, the noise created by the operation of the escapement mechanism is reduced to a point where it is substantially eliminated with the little remaining sound caused by the operation changed in pitch to a degree where it is not objectionable to persons working near a machine during operation and does not effectively interfere with the work of these people. It is also less tiresome to the typist. A beneficial result is therefore secured, particularly in offices where many typewriters are used.

The invention claimed is:

1. The combination in a typewriter having a main frame having a back plate and an escapement wheel and dog mechanism operably mounted on a bracket formed of a flat plate, of a cushioned escapement mounting comprising a supporting plate, means detachably mounting the plate forming said bracket with one face engaged with one face of said supporting plate, means for mounting said supporting plate with the opposite face in frictional engagement with one face of said back plate of said main frame for limited movement, said frame and supporting

plate having registering apertures therein and shock absorbing means mounted in said registering apertures for retaining said plate against movement relative to said frame and absorbing shocks and impacts applied to said plate.

2. In a typewriter having a frame formed with a back plate and an escapement, a cushioned support for said escapement comprising a supporting plate mounted with portions in surface contact with said back plate, means resiliently retaining said plates in frictional surface contact for limited edgewise movement, said plates having aligned apertures therein, and resilient means engaged in said aligned apertures for normally retaining said plates against relative edgewise movement and absorbing shocks applied thereto by said escapement.

3. In a typewriter having a frame formed with a plate portion and a supporting plate for a carriage escapement, a cushioned mounting for said escapement comprising means for resiliently pressing said supporting plate into frictional surface contact with said plate portion for limited movement on the surface of said plate portion, said plate and plate portion having registering apertures therein, and resilient members mounted in transversely extending relation in said registering apertures, engaging the edges of said apertures and absorbing shocks caused by relative movement of said supporting plate to said plate portion for substantially reducing noise produced in the operation of said escapement.

4. In a typewriter having a frame formed with a plate portion and an escapement mounted on a bracket, a cushioned escapement support comprising a supporting plate having surface contact with said plate portion, means securing said bracket on said supporting plate for mounting said escapement, a plurality of attaching members mounted in spaced parallel relation on said plate portion and projecting through openings in said supporting plate, resilient members mounted on said members engaging said supporting plate about said openings and retaining said supporting plate in frictional engagement with said plate portion of said frame, said plate portion and supporting plate having registering apertures, resilient plugs engaged in said registering apertures, and means for compressing said resilient plugs into contact under pressure with said plate and plate portion for cooperation in retaining said supporting plate attached to said plate portion and absorbing shocks and vibration from said escapement to substantially reduce the operation noise thereof.
